UNITED STATES PATENT OFFICE.

JOHN T. QUIGLEY, OF BOSTON, MASSACHUSETTS, ASSIGNOR TO COSTMETER COMPANY OF BOSTON, MASSACHUSETTS, A CORPORATION OF MASSACHUSETTS.

FILING EQUIPMENT.

Application filed October 29, 1919. Serial No. 334,150.

To all whom it may concern:

Be it known that I, JOHN T. QUIGLEY, a citizen of the United States, and a resident of Boston, county of Suffolk, and State of Massachusetts, have invented an Improvement in Filing Equipments, of which the following description, in connection with the accompanying drawings, is a specification, like characters on the drawings representing like parts.

This invention relates to filing equipments and is more especially concerned with a file of the class in which the sheets are arranged in overlapping relationship, so that identifying matter placed on the overlapping margins of all sheets of one group is presented to view at one time. The invention aims to improve the sheet supports by which the sheets are supported in the usual panel or frame.

My invention will be best understood by reference to the following description, when taken in connection with the accompanying drawings of one illustrative embodiment thereof, while its scope will be more particularly pointed out in the appended claims.

In the drawings:

Fig. 1 is a front view of a filing equipment exemplifying my invention;

Fig. 2 is a sectional view on line 2—2 of Fig. 1;

Fig. 3 is an elevation of one of the sheets and its sheet-holder, the sheet being shown as it appears when unfolded;

Fig. 4 is a perspective view of one of the sheets and its sheet-holder, illustrating the manner in which the sheet is dismounted from and reassembled with the sheet-holder;

Fig. 5 is a cross-sectional view on an enlarged scale of a sheet and sheet-holder.

Referring to the drawings, and to the embodiment of my invention which is illustrated therein, I have selected for exemplification a file comprising a series of overlapping sheets 5, herein folded, each sheet thus presenting two leaves, as best shown in Fig. 5. The sheets are supported with their overlapping margins properly spaced,—that is to say, with the proper width of exposure for identifying matter,—by a series of sheet supports, each herein comprising two parts 6 and 7, one laterally rigid and longitudinally resilient, and the other later-

ally resilient and longitudinally rigid. In the present example, the part 6 is in the form of a bar of sheet metal, suitably stiffened or rendered laterally rigid by being given a channel-shaped cross-section,—that is to say by providing the same with a pair of flanges 8, best shown in Fig. 5. The bar 6 is herein rendered longitudinally resilient by the provision of resilient terminal portions 9, herein formed by bending the web of the bar laterally in suitable formation, such as that represented in Fig. 4. It should here be noted that the reinforcing flanges 8 of the intermediate portion of the bar terminate short of the resilient terminal portions 9, and hence do not interfere with the flexing of the latter. It should moreover be noted that the ends of the resilient terminal portions are free to yield in a direction lengthwise of the bar.

The sheets are herein suitably secured to their respective sheet-holders by introducing the laterally flexible longitudinally rigid parts 7 into the folds of the sheets, and preferably the latter are provided with perforations 10, through which such part is threaded, as clearly shown in Figs. 3 and 4. Preferably the part 7 is in the form of a resilient, tempered steel wire, and its length may be reduced by bending or flexing the same laterally in the manner illustrated in Fig. 4, thereby to dismount the same from and reassemble it with the bar 8, the terminal portions 9 of the latter to this end being provided with perforations 11 to receive the terminal portions of the wire 7.

The bars 6 are arranged in series edge to edge in the manner illustrated in Fig. 1 to maintain the proper width of exposure of the overlapping margins of the sheets 5. The flanges 8 and laterally bent terminal portions 9 assist in preventing the bars from over-riding one another. The bars are adjustably and interchangeably supported by suitable guides 12, herein of usual and well-known construction, provided with usual channels in which the terminal portions 9 of the bars are received. These channels are formed in a well-known manner by providing a sheet metal panel 13, whose marginal portions are bent to form inwardly facing flanges overlying the terminal portions 9 of the bars 6. At the left-hand side of Fig. 1, a portion of one of the flanged guides 12 is broken away, and

2
shown in section the better to illustrate the manner in which the terminal portions 9 are received in and guided by said guides.

Preferably, the channels are comparatively shallow, and the arrangement is such that the bars may be readily removed by simply exerting a sufficient pressure in a lengthwise direction to reduce the length of the selected bar by flexing one of its terminal portions; or, if desired, the bar may be removed by simply exerting sufficient pressure laterally or in an outward direction to cause the rounded resilient terminal portion to bend and ride out of the guide, in the manner illustrated in full lines in Fig. 2. When the portions are in place in the panel, the entire group is held against longitudinal displacement in the guides 12 by the use of additional stops, herein exemplified by upper and lower abutments 14.

It should now be evident that the sheets may be interchanged on their sheet-holders, and the latter may be interchanged at will, and, in making re-arrangements of the subject matter, the sheet-holders may be adjusted lengthwise of the guides 12, with the greatest facility.

Having thus described one embodiment of my invention, but without limiting myself thereto, what I claim and desire by Letters Patent to secure is:

1. A file comprising, in combination, a pair of opposed channels, a series of bars

having resilient terminal portions yieldingly received in said channels and having relatively rigid intermediate portions, a series of wires carried by said bars, respectively, and a series of overlapping sheets carried by said wires, respectively.

2. A file comprising, in combination, a pair of opposed channels, a series of bars having resilient terminal portions received in said channels and yieldable longitudinally of said bars, and relatively to the intermediate portions thereof, and a series of sheets carried by said bars.

3. A file comprising, in combination, a pair of opposed supports; a series of sheet-holders, each comprising two parts, one laterally rigid and longitudinally resilient, and the other laterally resilient and longitudinally rigid, said longitudinally resilient part being normally retained by said supports by reason of its longitudinal resiliency and being removable therefrom by longitudinally flexing the same to reduce its length, and said laterally resilient part being normally retained by said other part by reason of its lateral resiliency and being removable therefrom by laterally flexing the same to reduce its length; and a series of sheets held by said sheet-holders, respectively.

In testimony whereof, I have signed my name to this specification.

JOHN T. QUIGLEY.
